UNITED STATES PATENT OFFICE.

CHARLES F. DOEBLER, OF NEW YORK, N. Y.

HAMMER.

Application filed October 10, 1927. Serial No. 225,185.

My invention relates to hammers and, more particularly, to the ordinary claw-hammer type of such tools.

One of the objects of my invention is to produce a hammer having jaws supplementary to the ordinary claws for drawing nails in finishing work without injuring or marring the face on which the hammer rests during this operation. Another object is to increase the leverage action in drawing a nail. Still another object is to enable one to make an article of this description without introducing new and difficult problems of manufacture, such as have been encountered in prior attempts to supply the hammer with supplementary jaws of this character. A further object is to make the supplementary jaws removable and interchangeable. Other objects will appear from the detailed description which follows.

In the drawings, Figures 1 to 4, inclusive, refer to one form of my invention, and Figures 5 to 8, inclusive, to another form, the first form being the one preferred. Figures 1 and 5 are top views of the hammer embodying my invention, with the supplementary jaws in place. Figures 3 and 7 are similar top views, but with the supplementary jaws removed. Figures 2 and 6 are side views of the hammer, partly in cross section to disclose the arrangement of the supplementary jaws. Figures 4 and 8 are cross sections of Figures 1 and 5 along the lines 4-4 and 8-8, respectively.

Referring to the figures in detail, 1 is the handle, and 2 the head of the hammer, the latter being shown as having an ordinary rounded pole 4 at one end, and drawing claws 3 at the other. In the preferred form, the pole 4 is cut out at the top to permit the insertion of the flat piece 5 which is dovetailed into the pole, as shown. A hole 6 runs through the pole 4. The flat piece 5 is cut out in its central region in the form of a round hole 7 tapering to a point 8 in the direction away from the face 9 of the pole 4. The tapering edges are beveled, as shown at 10, widening inwardly. The hole 6 in the pole is in registry with the cut out portion of the flat piece 5. The flat piece 5 is held against lateral displacement by pins or screws 11.

In the other form of my invention, illustrated in Figs. 5 to 8, the pole 4 is cut to receive the yoke 12, secured to the pole by

screws 13. The pole 4 is again provided with a hole 6 which registers with the hole 7-8 in the upper part of the yoke 12, the latter hole being in every way similar to that shown in the preferred form, both as to shape and as to the beveled edges.

Attempts have been made in the past to make a hole similar to the hole 7-8 directly in the pole and right through it, but it has been found practically impossible and, certainly, inexpedient for manufacturing purposes to file the hole to the desired shape in this manner. In the present invention, only the straight hole 6 has to be made in the pole, which is a very simple matter, and the difficult operation of producing the hole of shape 7-8 is transferred either to the flat piece 5 or the yoke 12, making the operation quite practicable and inexpensive.

The operation of the device is so simple that it needs but a few words of explanation. When a nail is to be drawn in a finishing operation, the hammer is placed over the head of the nail (and this applies to the flat head as well as to the round head nail) in such a manner that the head of the nail passes into the hole 7 of the flat piece 5 or yoke 12, whereupon the hammer is moved so as to engage the nail by the jaws formed by the beveled edges 10 of the flat piece 5 or yoke 12, and the nail is drawn by gradually rotating the hammer on its head, using the claws 3 for leverage. This manner of drawing the nail offers a much greater leverage action than the use of the claws 3 in the ordinary way because of the longer movement possible in the operation of turning the hammer on its head about the claws 3 as a fulcrum. At the same time, the smoothness of the faces of the claws 3, as they rest on the material worked on, insures the latter against injury from contact with the hammer, as this frequently occurs when the nail is drawn by means of the claws 3, and the hammer rests against the material worked on with the irregularly shaped and roughly surfaced pole 4.

The hole 6, of course, is to permit the drawn nail to fall out or to be removed.

Should the flat piece 5, or yoke 12, become defective from use, or injured, it is a simple matter to replace them. In other words, the supplementary jaws formed in the flat piece 5, or yoke 12, constitute an easily replaced and interchangeable article.

Also, any ordinary hammer, not supplied with these additional drawing jaws, may be easily transformed into one so supplied by making the indicated changes therein.

5 While I have illustrated the device in connection with an ordinary claw-hammer, obviously, the supplementary jaws may be introduced into any other type of hammer having a suitable pole, and I do not mean 10 to restrict myself to the specific illustrations shown and described. Nor is one to assume that the supplementary jaws must necessarily be formed within a flat piece 15 like the piece 5, or a yoke, like the yoke 12, since the same kind of jaws may be formed within many other shapes separably attached to or inserted in the pole, and there are, of course, many known ways for fixing 20 a separable piece of metal to another piece of metal, in addition to the dovetailing or bridging manner illustrated herein as examples for the purpose of teaching the art in accordance with the statutes. Nor do I mean to restrict myself to the particular 25 form of the supplementary jaws as shown, since, clearly, the shape of the hole 7-8 may be modified in a great many ways without departing from the spirit and purpose of the invention.

30 Having fully described the invention, I claim:

1. In a hammer, a pole, a flat piece dovetailed into said pole and having a hole tapering to a point, the direction of taper 35 being away from the face of said pole, and inwardly widening bevels on said flat piece along the tapering edges of said hole, said pole having a hole therethrough registering with the hole in said flat piece.

40 2. In a hammer, a pole comprising a section separable therefrom and having a hole tapering to a point, and inwardly widening bevels on said separable section along the tapering edges of said hole, said pole having a hole therethrough registering with 45 the hole in said separable section.

3. In a hammer having a pole, a flat piece cut in the center to form drawing jaws and dovetailed into the top part of said pole, said pole having a hole therethrough registering with the hole formed by the cut in said flat piece.

4. In a hammer, a pole having a hole therethrough, a flat piece cut in the center to form drawing jaws and dovetailed into said pole, said hole in the pole registering with the hole formed by the cut in said flat piece, and means for securing said flat piece against lateral displacement.

5. In a hammer, a pole having a hole therethrough and comprising a section separable therefrom, said separable section having a tapering hole registering with said first mentioned hole, and drawing jaws formed in said separable section by inwardly widening bevels along the edges of said tapering hole.

6. In a hammer, a pole having a hole therethrough and comprising a section separable therefrom cut to form drawing jaws, said hole registering with the hole formed by the cut in said separable section, and means for securing said separable section in place.

7. In a hammer, a pole having a hole therethrough, and drawing jaws inserted into said pole over said hole.

8. In a hammer, a pole having a hole therethrough, and drawing jaws removably inserted into said pole over said hole.

9. In a hammer, a pole comprising a separable section, said pole, without said separable section, having a hole therethrough, and drawing jaws in said separable section over said hole.

10. In a hammer, a pole having a hole therethrough and comprising a removable section, and drawing jaws disposed over said hole and formed in said removable section by a tapering hole therein having inwardly widening beveled edges.

CHARLES F. DOEBLER.
